(73) Assignee: **National Sales Coordinator Co., Inc.**,
Fountain Valley, CA (US)

(57) **CLAIM**

(**) Term: **14 Years**

We claim the ornamental design for the cover for water conditioning tank, as shown and described.

(21) Appl. No.: **29/168,461**

DESCRIPTION

(22) Filed: **Oct. 1, 2002**

FIG. 1 is a perspective view of the cover for water conditioning tank of the present invention;

(51) LOC (7) Cl. **23-01**

FIG. 2 is an exploded perspective view thereof relative to a water conditioning tank that is shown in dashed lines; forming no part of the claimed design;

(52) U.S. Cl. **D23/207**

FIG. 3 is a top plan view thereof;

(58) Field of Search D23/207, 209;

FIG. 4 is a bottom plan view thereof;

210/140, 190

FIG. 5 is a front elevational view thereof, the back elevational view being a mirror image; and,

(56) References Cited

FIG. 6 is a left-side elevational view thereof, the right-side elevational view being a mirror image.
